PLATEN FOR ROLLING APPARATUS

Adolph W. Doderer, Chicago, Ill., assignor to
 Borg-Warner Corporation, Chicago, Ill., a corporation of Illinois

Application November 15, 1941, Serial No. 419,279

4 Claims. (Cl. 80—16)

This invention relates to disc rolling apparatus and particularly to a platen therefor.

It has been proposed to form a centrally apertured disc or other circular object by rolling and spinning the object from some intermediate diameter radially outwardly to expand the diameter of the object and also radially inwardly to decrease the size of the central opening. A method for forming circular objects in such a manner is described in a copending application of R. C. Ingersoll, filed November 3, 1941, Serial No. 417,600. In accordance with the Ingersoll method the central opening may be larger or smaller depending upon the starting diameter for the inward rolling. It is contemplated that by the proper selection of the starting diameter no waste will be produced except for that resulting from trimming the inner opening to its final size.

Where the rolling-in step is used for the formation of relatively large sized discs, such as those used for vehicle wheels, the central portion of the disc is usually quite thick so that the trimming operation for the central opening requires extremely large pressures and sturdy apparatus. It is also extremely important that the blank be accurately balanced. If the outer portion has been rolled first so as to provide a tapered cross-section, the tapered portion must be exactly centered in the trimming machine to preserve the balance in the blank. This requires that a definite point of reference be used in all related operations.

The principal object of this invention is to provide a means for obtaining a reference point during the rolling-in step on the blank which may be used to preserve a predetermined relationship in a succeeding operation on the blank.

Another object of this invention is to provide an apparatus to be used in the rolling-in step of the Ingersoll process or in a similar process wherein the central opening is formed at least in part in the rolling step, whereby the thickness of the material which must be removed by the trimming operation is materially reduced so as to make possible the use of lighter equipment.

Another object of this invention is to provide an improved apparatus for use in a rolling-in operation wherein different-sized openings may be preformed as desired.

Yet another object of this invention is to provide apparatus for use in a rolling-in operation wherein the central flat section usually provided for use in attaching the object to its support may

be made of various sizes to suit the requirements of the manufacturer.

These and other objects of the invention will become apparent from the following detailed description when taken together with the accompanying drawing in which:

Fig. 1 is a fragmentary elevation partly in section of an apparatus which is designed to roll a circular blank inward to decrease the diameter of its central opening;

Fig. 2 is an enlarged section taken through the support for the blank showing the novel pre-forming apparatus; and

Fig. 3 is an enlarged section taken through a modification of the invention.

Referring now to Fig. 1 for a brief description of the apparatus, said apparatus is comprised of a rotatable base 10 on which is mounted a platen 11 having a conical portion 12 and a substantially flat portion 13. This particular form of platen is shown for purposes of illustration only and not by way of limitation, it being understood that the platen may assume any form desired insofar as this invention is concerned. Rotatable with platen 11 is a plurality of lugs 14 in each of which is pivoted a centrifugal clamp 15, said clamp being comprised of a weight portion 16 and an operative portion 17. It is understood that other clamping means might be employed without departing from the scope of this invention.

A stationary frame 18 straddles rotatable support 10 and supports a roll head 19 which is reciprocable relative to platen 11. Said roll head 19 is provided with a roll carriage 20 in which is mounted a roll 21, said roll carriage 20 being traversable over the surface of platen 11 by means of a rod 22 secured to carriage 20 and connected to a double action hydraulic cylinder or other power means (not shown). Downward movement of roll head 19 is limited by means of lugs 23 on frame 18 which are interposed in the path of movement of adjustable blocks 24 secured to roll head 19.

A blank 25 having the form shown in Fig. 1 may be placed on platen 11, and when the latter is rotated, operative portions 17 of centrifugal clamps 15 contact the outer edges of the blank and hold the entire blank firmly against the platen. Since the centrifugal force developed in clamps 15 is a function of the square of the angular velocity of the platen, the clamping action increases as the square of the speed of rotation of platen 11.

The operation of the mechanism thus far described is as follows:

Assuming that a blank 25 has been placed upon platen 11 and that the latter is then rotated, so that clamps 15 hold blank 25 firmly against the platen, roll head 19 is lowered until blocks 24 contact lugs 23, and then roll carriage 20 is moved to the right from approximately the position shown in Fig. 1, contacting blank 25 substantially at the corner formed by the juncture of flat portion 13 and conical portion 12. Roll carriage 20 continues to move radially inwardly with respect to platen 11 until some point near the center of rotation of the blank is reached, whereupon further movement toward the right is arrested, roll head 19 is raised, and carriage 20 is returned to its starting position. Platen 11 is then stopped by some suitable means to permit clamps 15 to assume a releasing position and blank 25 is removed from the machine to permit the insertion of a succeeding blank to be rolled.

Referring now to Fig. 2 for a detailed description of the invention, it will be observed that platen 11 is formed from two sections 26 and 27, section 26 being piloted at 28 in a recess 29 in section 27. It is contemplated that inasmuch as roll 21 does not operate over the entire surface of platen 11, it is only necessary to furnish a hardened supporting surface on platen 11 for that portion of the blank which is to be operated upon by the roll. For this reason, section 26 of the platen need not be hardened but section 27 is hardened to withstand the pressures imposed thereon by the roll.

Section 27 is secured to section 26 by means of screws 30 and is removable from section 26 merely by removing said screws 30. It is also contemplated that different forms of blanks may be rolled by this process upon platen 11 merely by replacing section 27 by one appropriately formed. Thus if it is desired to form a blank having a longer conical portion and a correspondingly shorter flat portion, such a blank may be accommodated in the machine described merely by removing section 27 and substituting for it one having the proper length of conical portion and flat portion.

Section 27 is provided with an inner ridge 31 which is initially smaller in diameter than the diameter of the aperture in blank 25. This is shown more clearly in Fig. 1 wherein it is apparent that ridge 31 is of such a diameter that a considerable space is present between it and the edges of aperture 32 in blank 25. Ridge 31 is of lesser height than the ultimate thickness of the central portion of the blank after said central portion has been rolled. It is formed with a surface 40 which is preferably sloped inward with respect to the plane of the central portion of the blank, and with a sloping surface 36 which forms a central recess 37 for the reception of excess material. The slight inward slope or taper is desirable since without it, the blank may cool and shrink against the ridge thereby making it necessary to destroy the blank in order to remove it from the platen. If, however, the blank can be removed promptly upon the completion of the rolling operation so that it cannot cool sufficiently to cause it to bind against the ridge, surface 40 can be made perpendicular with respect to the plane of the central portion.

It is apparent that when roll 21 cooperates with blank 25 it moves the metal from the corner 33, formed by the junction of flat regions 34 of blank 25 with conical region 35, radially inwardly,

thereby progressively decreasing the size of opening 32 in the blank. Enough material is moved by the roll so that the entire space between ridge 31 and the initial opening 32 in the blank will be filled and any excess metal present will be forced over the edge of ridge 31 and thence down sloping surface 36 at the inner portion of the ridge into the recess 37 located at the center of section 27. Since ridge 31 is accurately machined, it will form a circular, accurately contoured indentation at the central portion of the blank. When the blank is removed from the platen after having been rolled, the circular indentation is used as a reference point for centering the blank in the next operation which may be a forming operation. Ultimately, the central opening is trimmed and the indentation may again be used as a reference point or pilot in the trimming machine, or it may be used to lighten the trimming operation, the trimming die being fitted into the indentation so that it is necessary merely to pierce a thin flash 38.

Obviously, ridge 31 may be formed at any point along the surface of section 27 and may have any contour. It may also be removable with respect to section 27 as shown at 31a in Fig. 3 to provide different sized pilots or locating indentations for the blank. Likewise, it is clear that any size or form of section 27 may be used as shown in dotted lines, for example, at 39.

Since the flash 38 may be made relatively thin, the subsequent trimming operation need not require very sturdy machinery. The recess formed by ridge 31 also functions to provide a means for centering the blank on the trimming die.

It is understood that the foregoing description is merely illustrative of a preferred embodiment of the invention and that the scope of the invention therefore is not to be limited thereto but is to be determined by the appended claims.

I claim:

1. A platen for a disc rolling machine wherein a blank having an irregular central opening is to be rolled inwardly toward its center, said platen comprising a supporting region for the blank and a central ridge removed from the irregular central opening, said ridge being shallower than the thickness of the disc immediately adjacent the ridge, whereby a recess is formed in the blank as the latter is rolled over the ridge, the recess facilitating piercing a central opening in the blank.

2. A platen for a disc rolling machine wherein a blank is to be rolled inwardly toward its center, said platen comprising a supporting region for the blank and a central ridge, said ridge having a side which is disposed at an angle to the plane of the blank immediately adjacent thereto and another side which is oblique to the plane of the blank whereby to form a pocket for excess material resulting from the rolling operation.

3. A platen for a disc rolling machine wherein a blank is to be rolled inwardly toward its center, said platen comprising a supporting region for the blank and a central ridge, said ridge being shallower than the thickness of the blank immediately adjacent thereto and said ridge having one side sloped radially inward with respect to the plane of the blank and an inner side sloped radially outward with respect to the plane of the blank, whereby excess material formed during the rolling operation is received in the central portion of the platen, said ridge serving to form a recess in the blank to facilitate piercing a central opening therein.

4. A platen for a disc rolling machine wherein a blank is to be rolled inwardly toward its center from an intermediate diameter, said blank being flat from said intermediate diameter radially inwardly and being conical from said diameter radially outwardly, said platen comprising a section adapted to contact and support a part of the conical portion of the blank, a second section adapted to contact and support the remainder of the blank, said second section being hardened and being removable from the first-mentioned section, and a ridge in said second

section adapted to form a recess in the blank as the latter is rolled in order to facilitate piercing a central opening therein, said ridge being shallower than the thickness of the blank immediately adjacent thereto, and having an outer surface which is perpendicular to the plane of the blank thereat and an inner surface which is oblique to said plane, said outer surface forming the edge of the opening to be pierced in the blank.

ADOLPH W. DODERER.
